(57) **CLAIM**

We claim the ornamental design for the light-emitting diode, as shown and described.

DESCRIPTION

FIG. 1 is the perspective view of the light-emitting diode

FIG. 2 is the front view thereof

FIG. 3 is the rear view thereof

FIG. 4 is the left side view thereof (the right side view thereof is a mirror image of this)

FIG. 5 is the top plan view thereof; and,

FIG. 6 is the bottom view thereof.

1 Claim, 2 Drawing Sheets

FIG. 1

FIG. 2

FIG. 3

FIG. 4

FIG. 5

FIG. 6
